DESIGN FOR A SUPPORT FOR REAR VIEW AUTOMOBILE MIRRORS

William H. Colbert, Brackenridge, Pa., assignor
to Liberty Mirror Works, a corporation of
Pennsylvania

Application July 12, 1935, Serial No. 57,602

Term of patent 14 years

To all whom it may concern:

Be it known that I, William H. Colbert, a citizen of the United States, and a resident of Brackenridge, in the county of Allegheny and State of Pennsylvania, have invented a new, original, and ornamental Design for a Support for Rear View Automobile Mirrors, of which the following is a specification, reference being had to the accompanying drawing, forming a part thereof, wherein:

Figure 1 is a side elevation of the support.
Fig. 2 is a rear elevation thereof.

The dominating feature of the design is the vertical clamping bracket which, as shown, is of wedge shape tapering in two directions, Fig. 1 showing the taper in one direction, and Fig. 2 the taper in the other direction, and having a smoothly rounded contour.

I claim:

The ornamental design for a support for rear view automobile mirrors, as shown and described.

In testimony whereof, I have hereunto subscribed my name this 10th day of July, 1935.

WILLIAM H. COLBERT.
